UNITED STATES PATENT OFFICE

136,596

DESIGN FOR A BARRACKS CASE OR SIMILAR ARTICLE

Stuart G. Robson, San Diego, Calif.

Application June 11, 1943, Serial No. 110,434

Term of patent 14 years

To all whom it may concern:

Be it known that I, Stuart G. Robson, a citizen of the United States, residing in the city and county of San Diego and State of California, have invented a new, original, and ornamental Design for a Barracks Case or Similar Article, of which the following is a specification, reference being had to the accompanying drawing, forming part thereof.

Fig. 1 is a perspective view of a barracks case or similar article in open position, embodying my new design; and

Fig. 2 is a rear elevation thereof in the closed position.

I claim:

The ornamental design for a barracks case or similar article, substantially as shown.

STUART G. ROBSON.
